UNITED STATES PATENT OFFICE.

HENRY F. STARRETT, OF CHICAGO, ILLINOIS; ASSIGNEE, BY MESNE ASSIGNMENTS, TO
STARRETT MANUFACTURING COMPANY.

PANEL-BOARD.

1,321,489.

Specification of Letters Patent. Patented Nov. 11, 1919.

Application filed May 17, 1913, Serial No. 697,983. Renewed April 2, 1919. Serial No. 287,099.

To all whom it may concern:

Be it known that I, HENRY F. STARRETT, a citizen of the United States, residing at Chicago, in the county of Cook and State 5 of Illinois, have invented new and useful Improvements in Panel-Boards, of which the following is a full, clear, concise, and exact description, reference being had to the accompanying drawing, forming a part 10 of this specification.

My invention relates to improvements in panel boards and has for one of its objects to improve the construction of panel boards so that they may be more cheaply manufactured than panel boards heretofore constructed in the commercial art, so that they will be stronger and more durable and so that the parts thereof may be readily assembled.

For the purpose of disclosing my invention I have illustrated in the accompanying drawings one embodiment thereof. In said drawings—

Figure 1 is a front elevation of the panel board embodying my invention;

Fig. 2 is a rear elevation of a portion of said panel board showing the inclosing casing in section;

Fig. 3 is a sectional view taken on the line 30 3—3 of Fig. 2;

Fig. 4 is a sectional view taken on the line 4—4 of Fig. 3;

Fig. 5 is a detail section taken on the line 5—5 of Fig. 1;

Fig. 6 is a perspective view of the insulating strips for the bus bars;

Fig. 7 is a perspective view of the securing means for said insulating strips;

Fig. 8 is a perspective view of one of the 40 anchor studs;

Fig. 9 is a perspective view of one of the distributing connector bars; and,

Fig. 10 is a detail sectional view showing a modified form of terminal connectors.

In the embodiment of the invention illustrated I provide an insulating base 1 which is preferably of slate and on which the various parts of the panel board are adapted to be mounted. The distributing conductors in the form of bus bars 2 and distrib-

uting connectors 3 are permanently mounted on the rear of the base and the equipment devices in the form of fuse receptacles 4, cut-out switches 5, binding posts 6, etc., are removably mounted on the front of the insulating base. The securing means for the fuse receptacles, binding posts, cut-out switches, etc., are all accessible from the front of the board so that after the board is once installed damaged parts may be replaced without removing the board from position and without disturbing any of the circuits of the board excepting those controlled by the damaged device. The slate base is made about one-third as thick as 65 the bases now used in the commercial art and is braced and the distributing conductors inclosed by a steel casing 7 which is secured upon the rear of the base.

In constructing my panel board, the slate base is first drilled with a proper number of holes arranged to receive anchor studs and other members which are adapted to extend through the base. These holes, with the exception of the holes for the terminal 75 connectors, are all of the same size so that all of the holes may be bored with a single drill, whereby the time for drilling the various holes in the board is reduced to the minimum, due to the fact that the operator 80 does not have to stop his drill from time to time to change to different sized bits.

After the slate base has been properly drilled the distributing connectors 3 are all mounted in position upon the rear of the base. 85 These connectors are formed from flat strips of copper or other good conducting material and each strip at each end is provided with a square or other non-circular hole to receive the hollow ends of the anchor studs 90 8. Each anchor stud is provided with a flat head 9 adapted to engage the front face of the panel board and has its stem arranged to extend through the hole in the panel board and through the non-circular hole in 95 the connector bar. After the anchor studs and connector bars are all arranged in position upon the insulating base the base is run through a suitable press and the hollow ends of the stems of the studs swaged or 100

riveted over the connector bars, during which process a portion of the metal of the stems of the anchor studs is forced into the angles of the square openings in the connector bars. This construction absolutely locks the connector bars to the back of the insulating base and at the same time locks the anchor studs against turning. After the riveting operation has taken place the 5 hollow stems of the studs are filled with solder which is permitted to flow over the bottom of the stud to insure a good electrical contact between the stud and connector bar and additionally aid in mechanically connecting the two together. Each stud is provided with a screw-threaded socket 10 which extends from the face thereof and is adapted to receive securing screws for the removable equipment fastened upon 10 the front face of the base and is also provided with a transversely extending slot adapted to receive downwardly extending projections on certain of the panel board equipments, such, for instance, as the fuse 15 clips 4, to prevent them from turning.

After the distributing connectors have been secured in position on the rear of the base, the bus bars are then arranged in position. These bus bars, it will be noted, are 20 formed of a plurality of strips of laminae of good conducting material and I have preferably formed them in this way so that the size of the bus bars may be graduated in accordance with the size of the current intended to be carried thereby; that is, at the 25 base or lower part of the bus bar which is required to carry the largest current it may be made of a number of strips and as the necessity for current carrying capacity decreases the strips may be decreased in number. These strips, it will be noted, are perfectly straight from end to end and the bus bars are secured in position by rivets similar in construction to those for securing the 30 distributing connectors in place, with the exception that they are longer, due to the fact that the bus bars are spaced farther from the base. Suitable spacer members 11 are inserted between the bottom of the bus bars and the insulating base to raise the bus bars sufficiently to permit the same to pass over or cross those distributing connectors which are arranged immediately beneath them. The rivets 12 for securing the 35 bus bars in position, as before stated, are longer than the rivets for securing the distributing conductor bars in position and have extending from their bottoms a pair of slots 13. These slots, when the solder is 40 poured into the hollow ends of the rivets after they have been swaged over the bus bars, permit the solder to flow into connection with the different laminae of the bus bars and thereby insure a good electrical

connection between the anchor studs and the 45 bus bars. Where the bus bars cross certain of the distributing conductors I insert between the bus bars and conductors strips of insulating material 14 which are preferably 50 held in position by means of down-turned lugs 15 which enter suitable openings 16 in the ends of the strips and extend downwardly from the ends of anchor plates 17. The anchor plates are secured in position 55 by the rivets 12 which pass through suitable openings formed in the plates. After the bus bars have been assembled in position the insulating strips 14 may be easily inserted between the distributing connectors which 60 they cross and the bus bars by turning the ends down until the openings 16 come opposite the lugs 15. Then, by releasing the ends of the strips, their natural resiliency will 65 spring the ends of the strips up into position with the lugs 15 fitting in the openings 16. The terminal connectors for the bus bars are provided with sockets 18 for receiving the ends of the bus bars and with an angle extension 19 into which is secured 70 a threaded bolt 20 adapted to pass through the insulating base and project above the same, a nut 21 being secured on the bolt to lock the terminal connectors in position. Suitable nuts are provided for securing the 75 ends of the leading-in wires to this threaded bolt 20. As a modification, however, of terminal connector, I have illustrated in Fig. 10 another form. In this form the extension 19 is enlarged and the terminal connectors secured in position by bolts 22. An extension 23 of the plate 19 passes through 80 the insulating base and is provided with a threaded socket 24 into which may be 85 screwed securing means for the ends of the 90 leading-in conductors.

The requirements for the different classes of panel boards sometimes necessitate the use of a main line knife switch, sometimes necessitate the use of main line fuses, sometimes both, and sometimes neither. It is extremely expensive to carry in stock the various sizes and kinds of panel boards, both with and without main line switches, main line fuses, or both, and to this end I have 95 mounted my main line switch, or, if necessary, the main line fuse or both, upon a separate insulating base 25. In the drawings I have illustrated a main line knife switch 26 as mounted on this base, but it will be understood that main line fuse clips may be 100 used in place of the main line switch if desired, or, if desired, the combination of the main line switch and main line fuse may be mounted on this separate insulating base. 105 The terminal connectors of the insulating base of the panel board proper and of the switch-carrying base may be electrically con-

nected by cross-bars 27. However, as the connection between the switch base and the panel board base proper would not be sufficient mechanically, if these connectors were 5 alone depended upon to connect the bases, the two bases have connected thereto on their rear the single steel inclosing casing 7. This casing not only serves the purpose of inclosing all of the parts on the rear of both bases, but mechanically supports the two insulating bases and so connects the two sections and braces the same that they become 10 in effect a unitary structure. This steel casing comprises a flat back having its sides and ends turned substantially at right angles thereto and adapted to engage the rear of the base, and in practice these sides and ends after they have been turned are welded 15 at the corners to aid in strengthening the casing. The casing is held in position on the base by bolts or screws 27^a which pass through the base and the back of the casing. As before stated, with the exception 20 of the openings for the terminal connectors, all the holes drilled in the base are of the same size, and as the bolts which pass through the base for the purpose of holding the casing in position are smaller than the openings drilled in the base, I provide 25 in each bolt hole a hollow rivet 28 which is fastened in the holes for the securing bolts and has a head 29 screw-threaded on its periphery for a purpose more fully hereinafter disclosed. The washer 30 over 30 which the rear end of the rivet is swaged is of the same thickness as the bus bar connectors, so that during the riveting operation this rivet may be swaged over with the others. 35

40 The bolts 27^a for securing the casing in position are arranged between the binding posts 6, and as the distance between these posts is short it is necessary that some insulating means be provided so that there will be no danger of short circuits between the 45 posts and the bolts due to moisture collecting on the face of the insulating base at this point. Therefore, I provide small insulating caps 31 which are internally screw-threaded and are adapted to screw over the 50 heads 29 of the rivets. The tops of these caps are provided with rotatable buttons 32 which have set in their face in a different-colored material, preferably white celluloid, 55 number pieces 33. These caps are held in position by means of spring washers 34 secured upon the ends of inwardly extending stems 35 and engaging beneath the annular flange 31^a. By this arrangement I not only 60 provide means for insulating the tops of the bolts or screws securing the casing in position, but also provide number buttons for indicating the different circuits. The different-colored insert 33 provides a good back-

ground for the numbers, and by making the 65 caps 32 rotatable, as shown, in event the board is turned in a sidewise position the numbers may be turned so that they will always be vertical and will not be difficult to read. 70

In order that the steel casing may be made as shallow as possible and at the same time avoid any danger of short-circuits at the point where the bus bars are arranged to meet the casing, as these bus bars are 75 raised above the slate base and therefore come in close proximity to the casing, I secure to the inside of the casing over the bus bars a strip of insulating material 36 to insure a thorough insulation between the back 80 of the casing and the bus bars. Also, in order that the casing may not be buckled or bent inward, I provide spacer members 37 which are of insulating material and are secured in position by screws 38 passing 85 through the insulating base.

The casing is provided with means whereby the panel board may be supported. Across the upper end of the casing I rivet or otherwise secure a cross bar 39 which has 90 vertical slots 40 in its ends, thereby forming hooks adapted to fasten over supporting screws or nails and from which the panel board may be hung. A similar bar 41 is secured at the bottom of the casing, but instead of having hooks formed therein the slots 42 are arranged transversely and engage suitable pins so that the lower end of the panel board will be locked against rocking. 95

100 While I have shown and described for the purpose of disclosing my invention a panel board embodying the same, it will be understood that my invention may be embodied in other forms of panel boards and 105 that various changes may be made in the panel board illustrated and described without departing from the spirit of my invention as set forth in the appended claims.

110 Having thus described my invention, what I claim as new and desire to secure by Letters Patent, is—

1. The combination with an insulating base, of bus bars and distributing connectors arranged on the rear thereof, rivets for securing said bus bars in position, at least one of said connectors crossing said bus bars, strips of insulating material removably inserted between said bus bars and crossing connector, and anchor plates held in position by the bus bar securing rivets and provided with angularly extending lugs arranged to fit in openings in said strips to hold the strips in position. 115

120 2. The combination with an insulating base, of distributing conductors arranged upon the back of said base, an inclosing casing for said conductors secured upon the 125

- 25 back of said base, bolts passing through said base and casing for securing the casing in position, and an insulating cap secured over the heads of said bolts on the face of the base.
3. The combination with an insulating base, of distributing conductors arranged upon the back of said base, a casing arranged upon the back of said base, a hollow 10 rivet extending through said base and having its head on the face of the base peripherally screw-threaded, a bolt extending through said rivet and casing for securing the casing in position and an insulating cap 15 internally screw-threaded secured on said rivet and over said bolt.
4. The combination with an insulating base of a panel board, of binding posts secured on the face thereof, a casing secured 20 upon the back of said base, bolts extending through said base and casing for securing the casing in position and disposed between said binding posts, and an insulating cup secured over the heads of said bolts to insulate the same from said binding posts.
5. The combination with an insulating base, of a plurality of distributing connectors secured upon the rear of said base, a plurality of bus bars also secured upon the 25 rear of said base, said bus bars being spaced apart from the base to permit the connector strips to pass thereunder, rivets extending through said base and through said bus bars for securing said bus bars in position, and spacer members interposed between said bus bars and the insulating base.
6. The combination with an insulating base, of a plurality of bus bars each formed of a plurality of laminations secured upon the rear thereof, rivets extending through 30 said base and through said bus bars for securing said bus bars in position, said rivets being hollow at their ends swaged over the bus bars, filled with solder and having the 35 walls slotted to permit the solder to flow to the various laminæ of the bus bars.
7. The combination with a panel board, of a base member comprising a plurality of insulating base sections electrical equipment 40 of the board mounted thereon, bus bars and distributing connectors permanently secured on the back face of at least one of said sections thereof, and a one-piece steel casing extending the combined length of said base 45 sections secured to the back thereof.
8. The combination with an insulating base, of bus bars and distributing connectors arranged on the rear thereof, anchor studs extending through the bus bars and connectors and having a soldered connection therewith to permanently hold them in place, at 50 least one of said connectors crossing said bus bars, strips of insulating material inserted between said bus bars and crossing

connectors, and anchor projections engaging in notches in said strips to hold the strips in position. 65

9. The combination with an insulating base, of distributing conductors arranged on the back of said base, a casing mounted on the back of the base, bolts extending through said base for securing the casing in position, and internally screw-threaded insulating caps covering the tops of said bolts and screw-threaded cap retaining members arranged beneath the heads of said bolts. 70 75

10. In combination, bus bars each comprising a plurality of laminations, rivets extending through said bus bars for securing them in position, said rivets being hollow, 80 filled with solder and having slotted walls to permit the solder to flow to the various laminæ of the bus bars.

11. In combination, bus bars each comprising a plurality of laminations, rivets extending through said bus bars for securing them in position, said rivets being swaged over, hollow, filled with solder and having slotted walls to permit the solder to flow to the 85 various laminæ of the bus bars. 90

12. The combination with a panel board base member comprising an insulating base, bus-bars and distributing connectors permanently secured upon its back, anchor studs permanently connected with said bus-bars and distributing connectors and extending through said base to the other face thereof, of a second insulating base having circuit opening devices secured on the front face thereof, detachable conductor screws 100 for connecting said circuit opening devices with the bus-bar terminals, and a one-piece steel casing extending the combined length of said bases and secured to the back thereof. 105

13. The combination with a panel board base member comprising an insulating base, bus-bars and distributing connectors permanently secured upon its back, anchor studs permanently secured to said bus-bars and distributing connectors and extending through said base to the front face thereof, of a second insulating base having circuit opening devices secured on the front face thereof, detachable conductor screws for connecting said circuit opening devices with 115 the bus-bar terminals, and a strengthening one-piece steel casing extending the combined length of said bases within the outer edges of the bases and secured upon the back thereof. 110

14. The combination with a panel board base member comprising an insulating base, bus-bars and distributing connectors permanently secured upon its back, anchor studs permanently connected with said bus-bars and distributing connectors and extending through said base to the front face thereof, of a second insulating base having circuit 120 125

opening devices secured on the front face thereof, detachable connector screws for connecting said circuit opening devices with the bus-bar terminals, and a sheet steel back-
5 ing having its sides and edges turned at right angles thereto and extending the combined length of said base and secured upon the rear of said bases.

In witness whereof I have hereunto subscribed my name in the presence of two wit- 10
nesses.

HENRY F. STARRETT.
